United States Patent Office

Des. 225,374
Patented Dec. 5, 1972

225,374

PIANO

Dennis Barket, Cincinnati, Ohio, and Winsor D. White,
Jr., Blowing Rock, N.C., assignors to D. H. Baldwin
Company, Cincinnati, Ohio

Filed Apr. 21, 1971, Ser. No. 136,307

Term of patent 14 years

Int. Cl. D17—01

U.S. Cl. D56—9

FIG. 1

FIG. 3

FIG. 1 is an angular perspective view of a piano embodying our new design.

FIG. 2 is a front elevational view thereof.

FIG. 3 is a side elevational view thereof.

The back of the piano (not shown) is conventional.

We claim:

The ornamental design for a piano, substantially as shown and described.
